[57] CLAIM

The ornamental eyewear and eyewear front, as shown and described.

DESCRIPTION

FIG. 1 is a front elevational view of an eyewear front embodying my new design;

FIG. 2 is a rear elevational view thereof;

FIG. 3 is a top plan view thereof;

FIG. 4 is a bottom plan view thereof;

FIG. 5 is a side elevational view thereof; and,

FIG. 6 is a front perspective view thereof;

The portion of the figures in broken lines shown for environmental purposes only and forms no part of the claimed design.

The broken line shown in FIGS. 1-6 is for illustrative purposes only and forms no part of the claimed design.
